M. BUCHHOLZ

CONTROLLING LIQUID INSULATED ELECTRIC APPARATUS

Original Filed Sept. 15, 1922

UNITED STATES PATENT OFFICE.

MAX BUCHHOLZ, OF CASSEL, GERMANY.

CONTROLLING LIQUID-INSULATED ELECTRIC APPARATUS.

Original application filed September 15, 1922, Serial No. 588,457, and in Germany January 19, 1922.

Divided and this application filed April 16, 1925. Serial No. 23,672.

My invention has reference to a method and means for protecting electric apparatus operating in an insulating liquid, such as oil transformers, oil switches, grounding throttling coils, resistances and the like, and it is one of the important objects of my invention to provide a device of very simple construction and great reliability and adapted to operate before extensive injuries to the apparatus to be protected can occur by 10 sparking, overloading or other disturbances.

My invention is particularly based on the fact that in the case of disturbances in the operation of the apparatus to be protected 15 or in the case of sparking or other irregularities of operation, or whenever such irregularities are imminent, as well as in the case of any ebullition or fermentation processes in the oil, serving as an insulating liquid, 20 bubbles of gases of decomposition are formed which can operate protective means, for instance an electric contact, either a working or a closed contact, which is adapted to switch out of circuit the apparatus to be 25 protected, or which will operate an alarm or annunciator device indicating the disturbance, or which is adapted to effect both kinds of operations. The gases formed by decomposition may influence the protective means 30 in different ways, this application being a division of my copending application Serial Number 588,457 filed September 15, 1922.

I may for instance utilize the movements of parts of the liquid arising in consequence 35 of a change of volume or the expansion of the liquid or from other causes incident upon the generation of the gases or oil vapors for varying the operative conditions of a protective circuit.

40 In the drawings affixed to this specification and forming part thereof, a device embodying my invention is illustrated diagrammatically by way of example.

In the drawings

45 Fig. 1 shows a protective device with a contact adapted to be closed by a movement in the insulating liquid in a transformer vessel, while

Fig. 2 is a plan view of the contact floats. 50 In the drawings *a* is the transformer vessel, *b* is the core of the transformer, *c* are the windings, *d* are the leading-in insulations for the conductors, *e* is the oil switch, *f* is the releasing coil connected with 55 it and *g* is a source of current which upon

the operation of the safety device excites 60 the coil, opens the oil switch and causes the switching-out of the apparatus.

The transformer vessel *a*, which is entirely filled with oil, is in communication with an expansion vessel *n*. The wires of 65 the protective circuit extend through a side wall of the expansion vessel and are connected each with one of a pair of floats *C* and *D*, the float *C* being considerably larger than float *D* and the two floats being connected by links *F*, while float *C* is attached to the side wall of the vessel *n* by links *E*. On the large float *C* is mounted a contact piece *G* extending above and in close proximity to another contact piece on the upper 75 surface of float *D* which is connected to the other terminal of the protective circuit, the floats being thus insulated from each other.

If a liberation of gases of decomposition 80 in the transformer vessel *a* causes agitation of the insulating liquid movement, this will act on the two floats *C* and *D* in a different manner. For while float *C* is attached to the wall of the vessel and has a larger 85 mass it will be less movable than the small float *D* linked to it and which, owing to its very small mass is easily movable. In consequence thereof a sudden movement will cause the small float *D* to be rocked before the large float *C* has had time to be set moving, and float *D* will therefore establish a contact with the piece *G*, thereby operating the opening of the oil switch *e* and throwing the transformer out of operation. 90 Other movements of the liquid particles caused by a liberation of gases or vapours will act in a similar way.

The contacting device according to this invention may be arranged at different places, 95 either in the interior of the main oil receptacle or, in the case of transformers, in combination with expansion vessels contained therein, or special spaces, tubes or similar instrumentalities may be provided 100 adapted for the reception of the contacting devices. The closing of the circuit may be effected both within as well as outside of the liquid.

The circuit to be controlled by the contacts referred to may excite either directly 105 or by the medium of an intermediate relay the releasing coil of an oil switch which interrupts the endangered circuit. In the case of apparatus the circuit of which does not 110

include an oil switch, as frequently occurs, for instance in the cases of transformers mounted in the field at wide distances apart, other provisions should be made for the purposes of this invention.

Besides the form of construction herein shown and described, the invention is susceptible of a variety of other modifications and forms of application of the principle of my invention all of which operate substantially in a similar manner. The means of connecting the contacting device with the releasing circuit and the switching means are open to changes and alterations without any material importance for the operation of the apparatus according to my invention which in its broad aspects comprises the operation of safety devices for electric apparatus or the like, adapted for operation by vapors, fumes, gases or similar emanations liberated and expelled from the insulating medium, and means adapted to be operatively influenced by such emanations, and connected to fuses or equivalent safety means, the instrumentalities shown and described in this specification as embodiments of these principles being susceptible of modifications without deviating from the spirit of my invention as set forth in the claims.

In the claims the term "gases" is meant to comprise also vapors and fumes.

I claim:—

1. Protective system for liquid-insulated electric apparatus comprising a container and a supply of insulating liquid surrounding the apparatus to be protected, a protective circuit and means adapted to be operated by an agitation of the liquid occurring in consequence of a decomposition of such liquid, for varying the operative conditions of said circuit.

2. Protective system for liquid-insulated electric apparatus comprising a container for said apparatus, a supply of insulating liquid in said container surrounding said apparatus, a protective circuit, and a contact device floating on said liquid and adapted to be actuated by agitation of the liquid occurring in consequence of a decomposition of such liquid for varying the operative conditions of said circuit.

3. Protective system for liquid-insulated electric apparatus comprising a container for said apparatus, a supply of insulating liquid in said container surrounding said apparatus, a protective circuit, an expansion vessel connected with said container and a contact device floating on the liquid in said expansion vessel and adapted to be actuated by agitation of the liquid occurring in consequence of a decomposition of such liquid for varying the operative conditions of said circuit.

4. Protective system for liquid-insulated electric apparatus comprising a container and a supply of insulating liquid, surrounding the apparatus to be protected, a protective circuit, a large float on the surface of said liquid, means limiting the movements of said large float, a small float linked to said large float and means for varying the operative conditions of said circuit on the small float being displaced relatively to the large float.

5. Protective system for liquid-insulated electric apparatus comprising a container and a supply of insulating liquid, surrounding the apparatus to be protected, a protective circuit, an expansion vessel communicating with said container, a large float on the surface of the liquid in said expansion vessel, and linked to the wall thereof, a small float linked to said large float and means for varying the operative conditions of said circuit on the small float being displaced relatively to the large float.

6. The method of controlling abnormal working conditions of liquid insulated apparatus which comprises causing a decomposition occurring in the liquid to produce an agitation of said liquid, and causing the agitation to vary the operative conditions of a protective means.

7. The method of controlling abnormal working conditions of liquid insulated apparatus which comprises causing a decomposition occurring in the liquid to produce an agitation of said liquid, and causing the agitation to vary the operative conditions of a protective circuit.

In testimony whereof I affix my signature.
MAX BUCHHOLZ.
